UNITED STATES PATENT OFFICE

GEORGE C. ERB, OF ROSELLE PARK, NEW JERSEY, ASSIGNOR TO AMERICAN CAN COMPANY, OF NEW YORK, N. Y., A CORPORATION OF NEW JERSEY

COVER FEED

Application filed March 22, 1928. Serial No. 268,807.

This invention relates to a can end feed device and has more particular reference to such a feed device which will separate stacked can ends so that they may be fed individually to a machine for performing further operations upon such can ends.

Such can ends are closely stacked into piles incidental to the various steps of manufacture, and before they can be fed to other machines they must be separated. This is a difficult operation where the ends are assembled in stack formation prior to the curling of the flanges, even when the can ends are stacked correctly which is not always the case. With my improved device, the can ends are quickly, easily and correctly separated irrespective of their position in the stack and at a great saving in time and cost.

It is an object of this invention to provide a can end feed device which will correctly separate stacked can ends to be fed to various machines during their manufacture.

Another object is to provide a device which will separate adjacent uncurled can ends irrespective of their position in the stack, whether normal or reversed.

Another object is to provide such a device which is positive in its action.

Numerous other objects and advantages of the invention will be apparent as it is better understood from the following description, which, taken in connection with the accompanying drawings, discloses a preferred embodiment thereof.

35 Referring to the drawings;

Figure 1 is a plan view of my device;

Fig. 2 is a sectional elevation of the device, showing the can ends in the magazine in several positions;

40 Fig. 3 is an enlarged cross-sectional detail of a supporting and separating unit;

Fig. 4 is a perspective of a large separator block, and

Fig. 5 is a perspective of a small separator block.

In the drawings, for the sake of clarity, I have omitted the supporting elements of my device and certain portions which will be pointed out later as forming no part of my invention.

A frame 11, suitably supported, carries a plurality of vertical or stack members 12, spaced about the periphery of the frame 11, with their inner surfaces substantially in alignment with an aperture 43 provided through the frame, which is of sufficient size to permit the passage of the can ends therethrough. A plurality of supporting and separating units 13 are provided about the aperture to support the stack of can ends in the magazine before their removal and to separate the can ends as they are withdrawn, the units being secured in suitable apertures of the frame 11 by means of set screws 17.

Each of these units 13 is composed of a body 14, side plates 15 and can end supporting and separating sliding blocks 18 and 22 together with their actuating mechanism. There are two types of the said supporting and separating blocks, each unit having one 70 large block 18 and a plurality or gang of small blocks 22 positioned above the large block 18. The large block has two beveled faces 19 at one end and a projecting lug 21 at the other. This projecting lug 21 engages a slot 44 in one of the side plates 15 and limits the movement of the block. Each small block 22 is similarly formed, having beveled faces 23 at one end and a projecting lug 24 at the other end. These lugs 24 engage in slots 45 80 formed in one of the side plates 15 to limit the movement of the small blocks. The large block is actuated by a plunger 25, which is pressed by a coil spring 26 held in place in an aperture in the body 14 by a set screw 27. 85

The gang of small blocks in each unit is backed by a block of resilient rubber 28, preferably in turn backed by a plate 29, which is pressed upon by a coil spring 31, held in a suitable aperture in the body 14 by a set 90 screw 32. The side plates are secured in place by bolts or small screws 16. It is to be noted that the coil springs 26 and 31 should be of sufficient strength to prevent an outward movement of the blocks due to 95 the weight of the stack of covers 42 in the magazine. Each unit is adjustable radially of the stack, carrying with it all of its can end-supporting blocks, when its screw 17 is loosened.

An arm 33, carrying a vacuum cup 35, is secured to a shaft 34 journalled in bearings formed in arms 41 extending from the frame 11 of the magazine. The shaft 34 may be actuated by suitable mechanism, not shown, such arrangements being well-known. A passageway 37 extends from the vacuum cup 35 through the arm 33 to the rear thereof where it connects to a hose 39 or other similar arrangement communicating with a source of vacuum.

In operation, a stack of can ends 42 is placed in the magazine and rests upon the supporting blocks of the supporting units 13. 15 The arm 33 is rotated until the vacuum cup 35 is in contact with the nethermost can end in the stack, when vacuum is applied and the cup grips the can end. The arm is then rotated downwardly, pulling the lowermost can 20 end with it. As the arm and cup continue to move downward, gripping a can end being removed from the stack, the can end moves past the gang of small blocks 22. There is sufficient resiliency in the rubber block 28 to 25 allow each of the small blocks to give back enough to permit the can end being removed to pass, the coil spring 31 providing a pressure adjustment. These small blocks 22 move back into their normal position as 30 the can end moves past, being urged by the rubber block 28 and the coil spring 31. The force exerted is also sufficient when the nethermost can end passes the gang of small blocks 22 to cause the large blocks 18 to be 35 moved back against the action of the plunger 25 and the spring 26 to free the said can end from the magazine, but as the can end moves past the blocks are forced back inwardly under the action of the spring to be in position to engage the next can end in the stack 40 when it is subsequently removed.

It will be understood that before the said action of the suction cup the stack may have been heavy enough to descend past some of 45 the upper supporting elements 22, and the can end so removed may be resting on the lowest supports 18.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

50 1. In a can end feed device and in combination therewith, a plurality of supporting and separating units, each unit comprising a plurality of spring-pressed blocks retractile to permit the passage of can ends, and means 55 for releasing said units and for securing

them in desired positions relative to the can ends.

2. In a can end feed device and in combination therewith, a plurality of can end supporting and separating units, each unit comprising a single, large spring-pressed detent and a gang of small detents, the gang being backed by a spring-pressed block of resilient material.

70 3. In a can end feed device and in combination therewith, a plurality of can end supporting and separating units, each unit comprising a single, large spring-pressed block presenting a double beveled face, and a gang 80 or small blocks positioned thereabove, each small block presenting a double beveled face, the gang being backed by a spring-pressed block of resilient rubber.

75 4. In a can end feed device, a magazine to store can ends to be fed in stacked relationship, a plurality of pressure actuated can end supporting units positioned adjacent the bottom of the magazine, the said units being adapted to separate the can ends as they are withdrawn from the magazine, each unit comprising a body and a plurality of spring-pressed sliding blocks, and a means to withdraw said can ends from the magazine, said means comprising a vacuum cup.

80 5. In a can end feed device, a magazine to provide storage for a stack of can ends, a plurality of units positioned at the bottom of the magazine adapted to support a stack of can ends and to separate adjacent can ends as they are withdrawn through the bottom of the magazine, each unit comprising a large spring-pressed block and a gang of small blocks placed thereabove backed by a spring-pressed block of resilient material, all blocks 90 presenting double beveled faces, and means to withdraw individual can ends from the bottom of the magazine, said means comprising a vacuum cup adapted to engage the bottom can end in the stack and to pull it through the supporting and separating units.

100 6. In a can end feed device, a magazine to provide temporary storage for a stack of can ends, a plurality of can end supporting and separating members positioned at the bottom of the magazine, each of said members having a vertical series of separating yielding supporting elements and means to pull individual can ends through said members, thereby separating said individual can ends from the remainder of the stack.

110 7. In a can end feed device, a magazine to receive can ends arranged in a stack, an upper set of can end supporting elements, a lower set of can end supporting elements, said elements being outwardly yieldable to the passage of a can end, and means for engaging the bottom can end to cause it to force outward the supporting elements which may engage therewith.

115 120 125 130 GEORGE C. ERB.
